UNITED STATES PATENT OFFICE

102,408

DESIGN FOR A TOMATO JUICE DISPENSER

Watson F. Barnhart, Milwaukee, Wis., assignor to Barnham Dispenser Company, Milwaukee,
Wis., a corporation of Wisconsin

Application August 24, 1936, Serial No. 64,542

Term of patent 14 years

To all whom it may concern:

Be it known that I, Watson F. Barnhart, a citizen of the United States, residing at Milwaukee, in the county of Milwaukee and State of Wisconsin, have invented a new, original, and ornamental Design for a Tomato Juice Dispenser, of which the following is a specification, reference being had to the accompanying drawing, forming part thereof.

I claim:

The ornamental design for a tomato juice dispenser as shown.

WATSON F. BARNHART.
